Attorney.

UNITED STATES PATENT OFFICE.

MOGENS C. A. SMEDEGAARD, OF HÖRNING, DENMARK.

OIL-BURNER.

1,267,811.

Specification of Letters Patent. Patented May 28, 1918.

Application filed August 16, 1917. Serial No. 186,635.

To all whom it may concern:

Be it known that I, MOGENS CHRISTIAN ANDERSEN SMEDEGAARD, a subject of the King of Denmark, residing at Hörning, Denmark, have invented certain new and useful Improvements in Oil-Burners, of which the following is a specification.

The present invention relates to oil-burning stoves and ovens; and it resides in the provision of means whereby it is possible to use oil or any other liquid fuel in almost any stove or oven without much alteration even though designed primarily for solid fuels.

15 The invention consists of a number of sockets placed above each other, so as to permit the fuel to drip down from one to another and while evaporating an intense combustion is obtained.

20 One embodiment of the invention is illustrated in the drawing:

Figure 1 shows a vertical section of the lower part of a stove,

Fig. 2 a cross section of the same,

25 Fig. 3 a modified detail.

The plate *b* forms the bottom of the fire space *a* in a stove and generally bears the grate. On the plate *b* a conical socket or funnel *c* is placed, the lower part of which 30 is turned up so as to form an annular channel or reservoir *d* which extends entirely around the funnel. On the top of the funnel *c* is another conical socket *e*, which is provided adjacent its lower edge with small, 35 internal projections *f* that are designed to rest on the top of said funnel *c*, so as to leave a space all the way around between the interfitting ends of the funnels. Another socket *g*, but smaller in size, is similarly fitted upon the upper end of the funnel *e*, and maintained in place thereon by its projections *h*. Several additional sockets or funnels can in the same manner be put on the top of each other according to circumstances.

45 The upper socket is covered by a plate *i*, resting on projections *j* leaving a little space between the funnel and the plate. A pipe *k*, provided with a valve *l*, leads from a tank 50 *m* provided with a charging hole *n*, and is carried into the stove at the bottom thereof, whence it passes up through the funnels into and through the plate *i*, the latter having a central opening in which the mouth of said pipe fits. Around this opening the plate *i* 55 is provided with small pipes or nipples *p*,

which project a little way above the plate, the bores *o* of said nipples forming air openings. The plate *i* has besides projections *q* on which the plate *r* rests, which latter is 60 sufficiently large as to cover the greater part of the stove.

On opening the valve *l* the liquid fuel passes through the mouth of the pipe *k* and spreads over plate *i*, from which it drips 65 down on the funnel *g* and thence down the other funnels. Now when the fuel is ignited the heat produced will heat the funnels which will convert the fuel dripping down their sides into gas and thus intensify 70 the combustion. Any kind of liquid fuel, even coal-tar, can be employed, and because air can pass through the spaces between the several funnels the combustion will be as intense and perfect as possible. The plate *r* 75 will direct the flames toward the walls of the stove, thus heating the said walls and in this way diffusing the heat in the room.

Instead of the projections *h* and *f* being cast on the internal sides of the upper funnel, they can be cast on the external sides of the lower funnel. The form of the funnels and the plates can be made to correspond to the stove, in which they are to be placed. The channel *d* serves to receive the fuel 85 which has not evaporated.

When very light fluid oils are used, a plate *s* will be used instead of plate *i*, as is shown in Fig. 3. This plate *s* has no air holes but is covered by a convex plate *t*. The fuel 90 will in this case be reduced to gas on the plate *s* and will be mixed with air when passing the edge of the plate *t*, and thus a perfect combustion will be obtained. In order to produce as much heat as possible, 95 the interior of the stove can be filled with broken bricks or the like above and below the burner.

Having now particularly described and ascertained the nature of my said invention 100 and in what manner the same is to be performed, I declare that what I claim is:

1. In an oil burner, the combination of a plurality of superposed conical members; a distributing plate mounted above the uppermost conical member and having a central opening; and an oil supply pipe having its outlet end fitted in said opening; said plate having air holes formed through it around said opening.

2. In an oil burner, the combination of a plurality of superposed conical members; a

distributing plate mounted above the uppermost conical member and having a central opening; and an oil supply pipe having its outlet end fitted in said opening; said plate being provided around said opening with a series of upwardly-projecting nipples, the bores of which form air holes.

3. In an oil burner, the combination of a plurality of superposed conical members; a 10 distributing plate mounted above the uppermost conical member and having a central opening; an oil supply pipe having its outlet end fitted in said opening; said plate having air holes formed through it 15 around said opening; and a spreader plate mounted above said distributing plate.

4. In an oil burner, the combination of a plurality of interfitting, frusto-conical members arranged in vertical series, the successive members increasing in size from top to 20 bottom of the series, so that the wall of each member will form a substantial prolongation of the next lower member; a distributing plate mounted directly upon the topmost conical member and having a central opening; and a spreader plate mounted directly 25 above the distributing plate.

M. C. A. SMEDEGAARD.
